UNITED STATES PATENT OFFICE

BRADFORD G. WARNER, OF FAIRFIELD, CONNECTICUT, ASSIGNOR TO THE WARNER BROTHERS COMPANY, OF BRIDGEPORT, CONNECTICUT A CORPORATION OF CONNECTICUT

FOLDING PAPER BOX

Application filed March 21, 1933. Serial No. 600,078.

This invention refers to improvements in display paper boxes, and relates more particularly to a double compartment foldable box which is adapted to be made from a single piece of paper stock by cutting and scoring the stock at one operation, and whereby the same may be shipped and stored in the flat and readily folded in such a manner as to provide two opposed envelope-like compartments that are adapted to be laid together, one upon the other to form a closure of the two and which, when opened up, may be displayed flat in alignment, or at an angle with respect to each other so that the contents of each compartment will be attractively exposed.

The blank for the box is prepared in such a manner as to be readily folded to form two oppositely disposed compartments that are open at their adjacent ends and their top sides so as to permit them to be readily filled and their contents attractively displayed. The two compartments may be filled separately, as for instance with envelopes in one compartment and writing paper in the other, or whereby a single article, as for instance a lady's sweater, wherein after being attractively folded, its upper portion can be tucked in one compartment and the lower portion in the other compartment, after which the two compartments can be laid over, one upon the other to form a closed package.

The box therefore possesses many advantages from a practical standpoint, not only regarding the cost of the box in the flat and the cheapness with which it may be packed and shipped, but also the further feature of being adapted for two different types of articles of an allied line, and also for holding legal papers as in transit or for filing purposes.

To these and other ends, the invention consists in the novel features and combinations of parts to be hereinafter described and claimed.

In the accompanying drawing:

Fig. 1 shows a perspective view of my improved foldable box in an open position, as in displaying of merchandise when contained

Fig. 2 is a side view, on a somewhat smaller scale, of the box shown in Fig. 1;

Fig. 3 shows a longitudinal view through the near end portion of the box, shown in Fig. 1, taken on line 3-3 of said figure; and

Fig. 4 shows a plan view, on a reduced scale, of a paper blank such as the box shown in Figs. 1 and 2 is formed of, but being folded to form the two separate compartments.

As before suggested, the container shown in Fig. 1 comprises two separate compartments A and B which are formed of a single piece of stock, and may be the same width and length, though the thickness of one is herein shown to be greater than that of the other.

This obviously is not necessary as they both may be of the same thickness and likewise adapted to be folded and laid one upon the other, as suggested by the illustration of Fig. 2, in a way to form a closed package. In this respect, it should be borne in mind that the distance represented by the lines a-a should be equal to or slightly greater than that of the combined length of the ends b-b of the two compartments so that the intervening portion c of the back, lying between the score lines d-d, will properly cover and close the ends of the two compartments when the same have been folded over or closed together.

Referring to Fig. 4, it will be seen that the blank is somewhat longer than wide, the two end portions being substantially alike except for difference in proportions in case the two compartments A and B are to be different in size. Each portion includes a back e, oppositely disposed sides f-f that are adapted to be folded over and inward along the scored lines g-h to form opposite edges i-i of the finished box, and inwardly disposed end portions j-j that align with each other when folded.

Extensions k-k are formed in alignment with the edges i-i so that when the same are turned up with the sides f-f, said extensions may also be disposed inward in alignment with each other to form an inner wall of the ends j-j of the box, and over which the closure member l is folded. This closure member is scored as at m and n to adapt its

edge portion *o* to be laid against the aligned extensions *k*—*k* and over upon the aligned end portions *j*—*j*, and further includes a tab end *p* that is turned in on scored line *q* over the free edges of the ends *j*—*j* and disposed inside of the compartment in a way to lock the several members together.

When a blank, as shown in Fig. 4, is folded, as above explained, there is formed a box having two compartments that may be used singly, as for separate articles, or can be used jointly as one container for holding a single garment that is adapted to be folded across its middle portion. In both instances the contents can be attractively displayed in the box when opened, and properly enclosed and protected when the two compartments are folded together.

Having thus described my invention, what I claim and desire to secure by Letters Patent is:

1. A folding box comprising two foldable members connected together by a closure portion, each of said foldable members comprising a back, oppositely disposed sides including creased edge portions adapted to be folded and disposed inward in alignment toward each other, extensions in alignment with each edge portion and also adapted to be folded and disposed inward in alignment with each other, the creased edge portions of one member being wider than those of the other member to form a larger compartment of one foldable member than the other, a closure member scored to fold over the said extensions when the latter are disposed inward in alignment, and having an end flap that is laid over the aligned edges of the inwardly disposed aligned sides to form compartments open upon their adjacent inner ends and top portions, and adapted to be closed when laid together.

2. A folding box comprising two foldable members connected together by a closure portion, each of said foldable members comprising a back, oppositely disposed foldable sides, including creased edge portions, adapted to be folded and disposed inward in alignment toward each other, extensions in alignment with each edge portion, the two aligned extensions on each side of the two integral foldable members being disposed in opposite directions and longitudinally of the said integral foldable members, a closure member scored to fold over the said extensions when the latter are disposed inward in alignment, and having an end flap that is laid over the aligned edges of the inwardly disposed aligned sides and bracing said extensions to form compartments open upon their adjacent inner ends and top portions, and adapted to be closed when laid together.

3. A folding box consisting of two integral foldable members from which two aligned compartments are formed, the top

and opposite adjacent portions of said compartments being open and adapted to be closed when folded over upon each other, the two members being connected by an end closure portion, each member comprising a back having oppositely disposed foldable sides, including creased edge portions, adapted to be folded and disposed inward in alignment toward each other, an extension on each foldable side in alignment with the edge portions, the two aligned extensions on each side of the two integral foldable members being of the same width as the edge portions from which they extend and disposed in opposite directions and longitudinally of the said integral foldable members, and adapted to be folded and disposed inward in alignment with each other, a closure member scored to fold inward toward that of a similar member and over the said extensions when the latter are disposed inward in alignment, and having an end flap adapted to be bent in over the aligned edges of the inwardly disposed aligned sides to retain them in place, to brace said extensions and to form like compartments open upon their adjacent inner ends and top portions, and closed upon their sides and outer ends and adapted to form a closed foldable box when laid together.

Signed at Bridgeport in the county of Fairfield and State of Connecticut this 18 day of March, A. D. 1932.

BRADFORD G. WARNER.
